(57) **CLAIM**

The ornamental design for a rotary mop with durable gear drive unit, as shown and described.

DESCRIPTION

FIG. 1 is a front perspective view showing a rotary mop with durable gear drive unit;

FIG. 2 is a front left perspective view thereof;

FIG. 3 is a rear right perspective view thereof;

FIG. 4 is a front view thereof;

FIG. 5 is a rear view thereof;

FIG. 6 is a left side view thereof;

FIG. 7 is a right side view thereof;

FIG. 8 is top plan view thereof; and,

FIG. 9 is a bottom plan view thereof.

1 Claim, 8 Drawing Sheets
